UNITED STATES PATENT OFFICE

132,701

DESIGN FOR A DECK OF PLAYING CARDS

John P. McManus, Ottawa, Ontario, Canada, assignor of forty-five per cent to Mary Agnes Beatrice McManus, Ottawa, Ontario, Canada

Application March 11, 1942, Serial No. 106,148

Term of patent 14 years

To all whom it may concern:

Be it known that I, John P. McManus, a citizen of the Dominion of Canada, residing at Ottawa, Province of Ontario, Canada, have invented a new, original, and ornamental Design for a Deck of Playing Cards, of which the following is a specification, reference being had to the accompanying drawing, forming part thereof.

Fig. 1 shows face views of the cards of one suit,

Fig. 2 shows face views of the cards of the second suit,

Fig. 3 shows face views of the cards of the third suit, and

Fig. 4 shows face views of the cards of the fourth suit of a deck of playing cards, showing my new design.

The backs of the cards are conventional.

I claim:

The ornamental design for a deck of playing cards, as shown and described.

JOHN P. McMANUS.
